UNITED STATES PATENT OFFICE.

WILLIAM L. BERGEN, OF BATAVIA, ILLINOIS.

MACHINE FOR THREADING BOLTS.

SPECIFICATION forming part of Letters Patent No. 284,168, dated September 4, 1883.

Application filed March 29, 1883. (No model.)

To all whom it may concern:

Be it known that I, WILLIAM L. BERGEN, a citizen of the United States, residing at Batavia, in the county of Kane and State of Illinois, have invented a new and useful Bolt-
5 Threading Machine, of which the following is a specification.

My invention consists in sundry improvements in bolt-threading machines, whereby the
10 chasers may be removed and reset quickly and accurately to the former position without the
expensive devices ordinarily used to secure this result; also, in a self-acting gage to set the
work by, in order to insure uniform length in
15 the thread, which the machine is designed to cut; also, in a more efficient and durable arrangement of the vise-jaws, enabling the operator to make the change necessary for holding different sizes and forms of work in much
20 less time than is required by the ordinary method, and, in general, in various improvements in mechanism to be described herein-after, designed to make a machine more easily operated, and more durable and efficient, than
25 those now in general use.

The machine embodying these principles is represented in the accompanying drawings, in which similar letters of reference indicate similar parts throughout the several views.

30 Figure 1 is an end elevation with carriage I and stop-bar J removed. Fig. 2 is a vertical section through the center of spindle *a* on the line *r s*, Fig. 1. Fig. 3 is a section of carriage I, vise-jaws G, and bracket F, on the line *t u*, Fig. 2. Fig. 4 is a plan of the machine with the cap *d* removed. Fig. 5 is a vertical section on the line *x y*, Fig. 4, showing the two positions of the gage-arm N. Fig. 6 is an enlarged front view of the revolving die-head, which
35 is principally composed of the spindle-head A, the shell B, and chaser-holders C. Fig. 7 is a section of same through the axis of spindle *a*, on the line *v w*, Fig. 6. Fig. 8 is a rear view of Fig. 6 with a portion of shell B cut
40 away to show a portion of the interior mechanism. Fig. 9 is an enlarged top view of a portion of the chaser-holder C, Fig. 6, showing the arrangement of the hollow flattened screw *m* and the adjusting-screw *p*, the point
45 of which bears against the outer end of the chaser *c*.

The machine is mounted on the column D, Figs. 1 and 2. The spindle *a* and die-head A, B, and C are rotated in the direction shown by the arrow in Fig. 1, by means of the gear *j*, 55 the pinion *i*, and the cone-pulley H, as shown in Fig. 2.

The bracket F, Figs. 1, 2, and 4, is fastened rigidly to the column D in such position that its upper edges are parallel with the axis of 60 the spindle *a*, and form a suitable track for the carriage I to travel on.

The carriage I, Figs. 2, 3, and 4, is a plate adapted to slide freely on the bracket F in line parallel with the axis of the spindle *a*, 65 being actuated by the hand-wheel P, connected with the pinion *f*, which meshes into the rack *g*, fastened to the inner edge of bracket F, Fig. 2. The carriage I carries two vise-jaws, G, Figs. 2, 3, and 4, which move in a line 70 transverse to the motion of the carriage. They are operated by a hand-wheel, R, Figs. 3 and 4, attached to the screw U, part of which screws into one vise-jaw with a right-hand thread, and part into the other with a left-hand 75 thread of same pitch. Furthermore, the screw U, Figs. 3 and 4, is so attached to the carriage I that it is free to revolve, but cannot move endwise; hence, it follows that the revolution of the hand-wheel R, Fig. 3, will result in 80 moving the vise-jaws G apart or together to a uniform distance from the center. The vise-jaws G are provided with two cylindrical steel grip-blocks, T, Fig. 3, which fit into suitable recesses in the jaws G, and have several grooves 85 cut longitudinally in their surfaces, of suitable form for holding the work which the vise is required to grip. Any of these grooves may readily be brought into position for use by revolving the grip-blocks T until the corresponding grooves are adjacent, as shown in Fig. 3, and any cylindrical object held between the grip-blocks T, as *h*, Fig. 4, will be in alignment with the spindle *a*, Figs. 2 and 4.

The stop-bar J, Figs. 4 and 5, is held in position by passing through the hole in the ear J', Figs. 1 and 4, and the hole in the carriage I at *i'*, Fig. 3. It is provided with the stop L, Fig. 4, to check the forward travel of the carriage I. It is also provided with the cam-stop K to check the backward travel of the carriage I, and also by means of the pin *l*, Fig.

4, working in connection with the spiral cam-slot cut in the edge of cam-stop K, to give a partial revolution to the stop-bar J when the carriage is run back.

5 N, Figs. 2, 4, and 5, is a gage-arm fastened to the stop-bar J in such position that when the carriage I is back as far as the cam-stop K will allow, the end of the arm stands across the line of the axis of spindle *a*, Figs. 2 and 4. In 10 this position it serves as a gage against which the end of the bolt *h*, Fig. 4, may be set before gripping said bolt in the vise G. As the carriage I moves forward and the pin *l* leaves the cam-stop K, the stop-bar J is caused to revolve 15 by the spiral spring *g'*, Fig. 4, until the gage-arm N occupies the position shown by the dotted lines at N', Fig. 5. The stop-bar J also operates the arm o, Fig. 4, which serves to close the die-head by means of the pin *n*, Figs. 20 4 and 8, acting on the pinion-arm Y, as will be fully described hereinafter. The revolving die-head, Figs. 6, 7, and 8, is composed of the spindle-head A, the shell B, which fits the periphery of A and may be partially revolved 25 upon it, and the chaser-holders C, which have pivots fitting accurately into holes in the spindle-head A, one of which is shown at C', Fig. 6, one of the chaser-holders being removed. The chaser-holders C are set in position to give 30 the proper cutting angle to the edges of the chasers *c*, Fig. 6, and they are held uniformly in that position by their outer ends, *i'*, bearing against the pins V, which are rigidly set in the edge of the shell B, Figs. 4 and 6. When the 35 chaser-holders C are in position for working, the shell B, Fig. 7, is prevented from turning on the head A by the clutch-pins *e*, which project from the inside of the shell B and enter a short distance into the head A, Figs. 7 and 40 8. It follows that if the head A be drawn out of the shell B, Fig. 7, until it shall clear the ends of the clutch-pins *e*, then the shell B may be partially revolved around the head A in the direction indicated by the arrow in Fig. 6, 45 and by reference to the same figure it is obvious that this motion, by changing the relative position of the pins V to the chaser-holders C, will allow the chaser-holders C to revolve on their respective pivots in the same 50 direction as the shell B, which results in moving the cutting-ends of the chasers *c* away from the center and out of the thread they have cut in *h*, Fig. 4.

Fig. 9 represents a device for adjusting the 55 chasers *c* in the chaser-holders C. *m* is a hollow screw, which screws to a shoulder in the chaser-holder C at the outer end of the slot that holds the chaser *c*. *p* is a set-screw running through the center of the hollow screw *m*, so that its point extends into the slot and bears against the outer end of the chaser *c*, 60 Fig. 9. Thus, after the hollow screw *m* has been removed from the chaser-holder C, Fig. 9, it may be reset to its former position with the 65 utmost accuracy by screwing it firmly against the shoulder. By turning the set-screw *p* in the hollow screw *m* any desired adjustment of

the chasers *c* may be made, or they may be set in sufficiently to be recut by a master-tap, which operation may be repeated, when necessary, until the chasers are less than half of their original length. In order to save the operator's time in making changes, the sides of the hollow screws *m*, as shown in Fig. 9, are flattened or slabbed, so that by holding the 75 flat sides to correspond with the sides of the slot the screw *m* may be inserted directly into the chaser-holder C almost to its shoulder, when a quarter-turn will tighten it to place with the flattened sides perpendicular to the 80 sides of the slot, thus making a very simple, accurate, and efficient adjustment for the chasers *c*, this being a very important point in all threading devices when separate chasers are used.

85 A device similar to the foregoing, except that the hollow screws *m* were not flattened, as above described, has been used in a die-head formerly patented to me, No. 244,427, (screw-cutting.)

90 To operate the machine, the bolt or rod to be threaded, *h*, Fig. 4, is placed between the vise-jaws G, so that the left-hand end touches the gage-arm N, when it is firmly gripped by the vise. The stop L, Fig. 4, is then set on 95 the stop-bar J at such a distance from the carriage I as will allow sufficient travel to cut the length of thread required. The carriage I, Fig. 4, is then moved to the left by means of hand-wheel P, until the revolving die-head engagess the rod *h*, and continues to draw the carriage forward in the process of cutting the thread. When the carriage I has reached the stop L, the drawing of the rod *h* pulls the spindle-head A out of the shell B, (which cannot 100 move laterally, being held back by the swivel-clamp *b*, Fig. 7,) until it is clear of the clutch-pins *e*, Fig. 7, when the pressure of the rod *h*, Fig. 4, on the ends of the chaser *c*, exerted through the holders C on the pins V, Fig. 6, will be sufficient to revolve the shell B on the head A until the chasers *c* are clear of the thread they have cut, when the rod *h*, Fig. 4, may be 105 directly withdrawn by moving the carriage I to the right to its former position. The process by which the die-head is closed ready for another operation may be understood by referring to Fig. 8, in which Z represents a 110 toothed segment fastened to the back of the spindle-head A.

115 Y is a pinion meshing into the segment Z. It is provided with a shaft extending through the back of the shell B, which forms a suitable journal. Said shaft terminates in a crank or arm, which lies closely against the back of the shell B, Fig. 7. From the foregoing description and reference to Fig. 8 it will be seen that any revolution of the pinion Y on its axis will cause, by means of the segment Z, a partial revolution of the head A in the shell B, and, 125 conversely, if the head A be turned with reference to the shell B, the pinion Y will be revolved on its axis; but if the head A and the shell B be rotated together, the relative posi- 130

tion of the pinion Y will not be changed thereby. The case last described is operative when the machine is at work and the shell B is held in position by the clutch-pins e. In this position of the die-head the pinion-arm Y, Fig. 8, is so adjusted that its outer or free end passes at every revolution of the die-head just inside of the closing-pin n, (which is operated by a device independent of the die-head, as will be described later,) as may be seen by reference to Fig. 8. The partial revolution of the shell B on the head A, which takes place when it is released from the clutch-pins e, will cause the pinion Y to revolve on its axis until the pinion-arm takes the position shown by dotted lines at Y', Fig. 8, in which position it will evidently come in contact with the closing-pin n during the revolution of the die-head, which will result in turning the pinion 20 on its axis until the end of the pinion-arm again passes inside of the closing-pin n, when the head A will engage the clutch-pins e and the die-head be once more in position for work.

As the closing-arm o, Fig. 4, is fastened to the stop-bar J, the pin n will occupy the position relative to the die-head (shown in Fig. 8) only when the carriage I is back against the cam-stop K. When the carriage I is in any other position, the arm o occupies a vertical 25 position similar to that of the gage-arm shown at N', Fig. 5. In this position it cannot close the die-head, which may thus be left open as long as desired, and then closed by bringing

the carriage against the stop K, when the partial revolution given to the stop-bar J by the pin l working against the spiral edge of K will bring the closing-pin at the end of arm o into the position shown at n, Fig. 8, in which position it will close the die-head, as already shown.

Having thus described the various principles and functions of my bolt-threading machine, what I claim, and desire to secure by Letters Patent, is—

1. The combination of the spindle-head A, 45 the shell B, the pinion Y, and the segment Z, for the purpose specified and shown.
2. The combination of the cam-stop K, the stop-bar J, the closing-arm o, the pinion Y, the segment Z, the head A, and the shell B, substantially as and for the purpose specified. 50
3. The combination of the carriage I, the cam-stop K, the stop-bar J, and the gage-arm N, substantially as and for the purpose shown and described. 55
4. The hollow screw m, having two sides of the thread flattened sufficiently to allow it to enter directly into the slot in chaser-holder C, combined with the adjusting-screw p and chaser-holder C, substantially as and for the purpose specified. 60

WILLIAM L. BERGEN.
